CIGARETTE DISPENSER AND LIGHTER

Richard Mayer, New Rochelle, N. Y., assignor
to Francis C. Copeland, San Francisco, Calif.

Application June 21, 1935, Serial No. 27,666

20 Claims. (Cl. 312—80)

This invention relates to cigarette dispensers and lighters and while adapted for general uses in this connection is particularly designed for use on automobiles and there intended to be mounted in convenient and accessible position with reference to the driver to permit a cigarette to be dispensed and ignited, so that it may be manually removed from the device and placed between the lips of the smoker in smoking condition.

Devices of this general character have heretofore been suggested and the present invention is directed more particularly to improvements in devices of this kind in order to render the same more convenient and efficient in operation and to overcome certain disadvantages which have been found in the devices of the prior art.

The invention therefore resides in the novel features of construction hereinafter more particularly set forth in the annexed specification, shown in the accompanying drawings, and set forth in the appended claims.

The accompanying drawings illustrate one practical embodiment of the invention, but the construction therein shown is to be understood as illustrative, only, and not as defining the limits of the invention.

Figure 1 is a perspective view of a cigarette dispenser and lighter embodying the present invention, the same being shown in normal, non-dispensing condition.

Figure 2 is a perspective view of the main portion of the structure with the cover and mounting element removed.

Figures 3 and 4 are perspective views of different structural elements of the device removed from the remainder of the structure.

Figure 5 is a side elevation, partly in section, of a lighting element embodied in the structure.

Figure 6 is a fragmental section perspective showing the dismantled body of the structure.

Figures 7 and 8 are transverse central sections through the structure showing the manner in which the cigarettes are dispensed.

Figure 9 is an underneath plan view of that part of the device shown in Figure 4, with the same partially dismantled, in the interest of clearness.

Figure 10 is a plan view of the body of the structure with certain parts removed and other parts broken away.

Figure 11 is a section on the broken line 11—11 of Figure 10 with the cover in place.

Figure 12 shows an ash receiving accessory which may be used if desired.

Figure 13 is a fragmental perspective of a modified form of ignition element and electrical connections therefor.

Figure 14 is a section on line 14—14 of Figure 13.

Figure 15 is a side elevation of a modified form of mounting bracket.

Figure 16 is a section on line 16—16 of Figure 15.

Figure 17 is a plan view, partly in section, of a modified form of clamp.

Figure 18 is a fragmental view of parts shown in Figures 3 and 4, but showing a modified form of construction.

The device of the present invention comprises a body 1 which constitutes a receptacle having an open top and provided across the lower portion of its front with an outlet opening 2. The open top is normally adapted to be closed by a cover 3 mounted on hinge pins 4 for pivotal movement. The receptacle and its cover may be made of any appropriate shape and of any suitable material, but, for the purpose of illustration, I have shown said receptacle and cover as molded from bakelite, composition or any other suitable material, as this method of manufacture may be accomplished economically and permits of the incorporation in the structure of aesthetic designs and shapes.

Positioned within the receptacle is a false bottom 5, as shown in detail in Figure 3. It is preferably stamped up from sheet metal and is provided at its opposite ends with flanges 6 and 6'. The flange 6 occupies a plane normal to the plane of the body of this false bottom, while the flange 6' is positioned askew, as shown, so that the upper free edge of the flange 6' is parallel to the upper edge of the flange 6, while the lower portion of the flange 6', where it joins the body of the false bottom, is out of parallel, as shown, so that the front edge of the false bottom is of less width than the rear edge or the top.

The dot and dash line in Figure 3 is drawn parallel to the flange 6 and shows the amount of skew, i. e., the amount to which the flange 6' is drawn in. The purpose of this arrangement is to preclude cigarettes fed from the forward edge of the false bottom, as hereinafter described, from falling upon the top or fouling a subjacent lever 38, the function of which is to impress a cigarette into cooperative relation with a lighting element, as will be presently explained. The same result may be accomplished in other ways without departing from this invention.

When the false bottom is positioned in the

receptacle, the flange 6 cooperates with one end portion of the latter to form an enclosure in which may be housed the lighting element of the structure. Said false bottom is adapted to be mounted within the receptacle, so as to slope toward the front opening 2 of the latter. It is rigidly mounted in place by means of a bolt or rivet 7 which passes through a boss 8 molded into the interior of the receptacle and shaped at its upper end to impart the proper pitch or slope to the false bottom 5, as shown best in Figures 6-8. The flanges 6 and 6' of the false bottom are more or less resilient and are adapted to bear with spring pressure against the opposite end walls 15 of the receptacle, so as to preclude rattling under vibration.

It will be noted from Figure 6, in particular, that the upper end of the boss 8 is externally rabbeted as at 9 and the false bottom seats upon the upper extremity of the boss forming between the false bottom and the base of the rabbet a clearance space for a slide 10.

The slide 10 is preferably stamped from sheet metal and comprises a substantially flat plate 11 having depending flanges 12 and 13 at its opposite lateral edges and provided at substantially its center with an elongated opening 14, the width of which is substantially equal to, though slightly greater than the reduced upper end of the boss 8. The slide is adapted to underlie the false bottom in facial engagement with the latter and with the opening 14 embracing the reduced upper end of the boss 8 to be guided by the latter, the inclination of the parts 5 and 11 being such that the slide, when drawn forward, will be extended through the front opening 2 of the receptacle. To further guide the slide for operation, the lower edges of the flanges 12 and 13 are adapted to ride upon inclined tracks 15 formed at the opposite ends of the receptacle and on the interior thereof, as shown in Figure 6, so that said slide will be properly guided for sliding movement and at the same time held in face abutting relation with the under surface of the false bottom 5.

The false bottom is, as stated, mounted rigidly in the receptacle, while the slide is mounted for reciprocating movement, but both of these parts have a length less than the front to rear dimension of the receptacle, so that, when the slide is in retracted position, as shown in Figure 7, with the front end of the opening 14 against the boss 8, which limits its movement in this direction, the front edge of the slide will be below and slightly back of the front edge of the false bottom and said false bottom is provided with spaced apart slots 16 to form between them a tongue 17 of resilient character, and the forward edge of which is slightly turned down, as shown at 18, to form a lip, which, when the parts are positioned, as shown in Figure 7, bears over the forward edge of the slide and resiliently holds the latter in this retracted position, so that the slide will not inadvertently move forwardly under vibration or rattle.

The forward edge of the slide is provided with a turned down flange 19, the greater portion of the width of which is cut away intermediate its ends, and the remaining parts of this flange are extended downwardly and outwardly and rolled 70 to provide hook-shaped rests 19 and 20 spaced laterally from one another. The central cut away portion of the flange 19 is bent under, as shown best in Figures 7, 8, and 9 to provide a rearwardly extending lip 21, which is perforated, as shown at 22, and these perforations form ele-

ments of a hinge connection by which a door or closure member 24 may be associated with the front opening 2 of the receptacle.

The door or closure member 24 is preferably made from sheet metal and is in the form of a channeled section provided at its rear with hook-shaped tongues 23 which pass through the perforations 22 and serve to hingedly mount the closure on the slide. The closure is of a width substantially equal to the width of the front opening 2 and is of such size and shape, that, when the slide is retracted into the receptacle, the lower edge 2' of the front opening will cooperate with said closure to produce a camming action which will pivotally move the closure into the position shown in Figure 7, wherein it will completely close the front opening 2. Said closure, however, is provided intermediate its ends with a finger piece 25 stamped from the closure and projecting into accessible position, as shown best in Figures 1, 7, and 8, so that said finger piece serves as a convenient means of withdrawing the slide, it being clear that, if the finger piece is grasped and pulled forward, it will draw the slide with it into the forward position of the latter, as illustrated in Figure 8. The pivotal connection, however, between the slide and the closure is at the rear edge of the latter, and, consequently, when the hold on the finger piece is released, the closure will swing down into the position shown in Figures 8, 2, and 4.

From the structure which is thus far described, the operation of the device in the dispensing of a cigarette will be apparent, for it will be noted that when the parts are in the closed position shown in Figure 7, the cigarettes in the receptacle will gravitate down the inclined surface of the false bottom 5 to the forward edge thereof and will tend to fall through the space between the forward edge of the false bottom 40 and the front wall of the receptacle to the end that one of them may gravitate into position on the rests 19 and 20. The proportions of the parts, however, are such that when one of the cigarettes is occupying a position on the rests, it will support the superimposed cigarettes above the inclined plane of the slide plate 11, and, consequently, when the finger piece 25 is grasped and the slide pulled forward, the slide will operate as a damper across the space between the front edge of the false bottom and the front wall of the receptacle and thus preclude other cigarettes from falling through this space. Furthermore, in order to clear the cigarettes out of the way, and preclude them from becoming deformed or pinched, I preferably form on the slide camming projections 26 operating through the slots 16 of the false bottom and serving to lift the cigarettes slightly in the vicinity of said space, so as to lift them up out of the way as the slide is pulled forward. By this arrangement, the forward movement of the slide dispenses the cigarettes one by one, i. e., it moves one cigarette into accessible position exteriorly of the receptacle and when the closure falls away into the position of Figure 8, the cigarette is in convenient position to be picked up by the prospective smoker.

An important feature of this invention resides in the association with a device of this character of novel and efficient lighting means, so that, when the cigarette is removed from the rests 19 and 20, it will be lit and ready for smoking. To this end, the depending flange 12 at one end of the slide is made to project forward

beyond the body of the slide and beyond the end of a cigarette supported by the rests 19 and 20 and at this projecting portion of the flange 12 is mounted a lighting unit designated generally by the reference character 21. This unit embodies a coil of electrical resistance wire 28 mounted in a metallic cup 29 to the back of which is riveted a clip of yoke 30. The rivet 31 secures the yoke to the cup 29 through an interposed body of insulation 32 which insulates the cup from the rivet and from the yoke 30. One end of the heating coil is connected to the cup 29, and the other end is grounded on the rivet 31 which is insulated from the cup. The yoke 30 is adapted to be slipped over the projecting portion of the flange 12, which is offset, as shown at 33, to properly position the yoke and hold it in place with the cup 27 in alignment with the cigarette supported by the rests 19 and 20. When thus clipped in place, one end of the heating coil is grounded through the rivet 31 on the flange 12, while the exterior of the cup 29 bears against a spring contact 34 projecting into engagement therewith and firmly supported on the under side 25 of the slide plate 11 by means of tongues 35. An insulating sleeve 36 insulates the contact 34 from the slide plate 11 and from the tongue 35, while the rear end of the contact 34 extends beyond the sleeve 36, as shown at 37, and forms a second 30 spring contact normally free from engagement with anything, when the slide is retracted, as shown in Figures 9, 10, and 11. There is, however, mounted on the receptacle a fixed contact 38 in the path of contact 37, as shown in Figure 35 11, so that, when the slide is pulled out, the contact 37 engages with the contact 38, and by so doing includes the lighting element in an appropriate electrical circuit with the result that the lighting element glows. With this arrangement, the lighting element is energized when the 40 slide is pulled out, and is de-energized when the slide is retracted.

In a device of this kind, it is desirable that the cigarette to be ignited should be pressed positively toward the ignition element. Consequently, I provide novel and efficient means for this purpose. This means comprises a lever 39 in the form of a bar, best shown in Figures 9, 10, and 2. The lever is fulcrumed at 40 and from the fulcrum, the work arm of the lever extends through an opening 41 in the rest 19 into a position to engage the end of the cigarette opposite the lighting unit. The power arm of the lever extends rearwardly from the fulcrum 40 and is offset at 42. Beyond the offset portion, there is a straight part 43 terminating in a curled end 44, all as clearly shown in Figures 9 and 10.

Mounted upon the base of the receptacle and on the interior thereof are upstanding posts 45 and 46, which are adapted to cooperate with the lever 39, as best shown in Figure 10; when the slide is pulled out, the offset 42 engages with the post 45 and produces therewith a camming action which serves to force the lever into the dotted line position of Figure 10 to bring the outer end of the lever into engagement with a cigarette supported by the rest 19 and 20, and to thus force said cigarette into engagement with the ignition element. When the slide is pushed in, the curled end 44 engages with the post 46 to force the lever back into its retracted position. This lever is made of relatively light material and is preferably resilient, so as to produce a yielding pressure on the cigarette sufficiently gentle as not to damage the same, but sufficiently firm to

insure proper engagement between the cigarette and the lighting element. A marked advantage in this structure is that there are no independent springs or other elastic means to get out of order, while the resilient lever is sufficiently long to minimize fatigue thereon.

In my experience with cigarette dispensers embodying lighting features, I have found that the lighting element is very apt to stain a cigarette or discolor the same through contact with the hot element, while a cigarette is in the position to be dispensed, but before being brought into dispensing position. This produces an unsightly appearance which is undesirable. I consequently provide in the apparatus of this invention means which definitely eliminates this objection and furthermore makes it impossible for a cigarette to be inadvertently ignited in a non-dispensing position. This I accomplish in a very economical way by stamping up from the door or closure a forwardly projecting lip 47 which, when the slide is retracted and the closure closed, is positioned to overlie the end of the ignition element to form a closure for the latter. A cigarette falling into the position of Figure 7 is thus protected by the lip 47 directly adjacent its end and between it and the lighting element and this lip remains in this position until the slide is pulled out and the closure permitted to drop into the position of Figure 8. It is to be noted, however, that the lip 47 may be made sufficiently large that, when the closure drops into the position of Figure 8, it does not entirely remove the lip from the end of the cigarette. On the contrary, the lip may still project slightly over the end of the cigarette. As a result, when the lever 39 forces the cigarette in the direction of the ignition element, it does not force the cigarette into actual contact with said element, but merely into a position very closely spaced with respect to the latter.

The arrangement described permits of a more ready supply of oxygen to the end of the cigarette during ignition thereof and thus expedites the lighting of the cigarette. If desired, however, the lip 47 may be made slightly smaller, so as to withdraw entirely from the end of the cigarette when the closure is swung down, so that the cigarette may actually contact with the ignition element during the lighting of such cigarette.

Instead of forming the shield 47 as a lip upon the closure of the device, I may, if desired, form said lip upon the flange 6 of the false bottom, as shown at 47' in Figure 18 and provide a slot 47² in the slide to receive this shield when the slide is drawn into dispensing position. When the slide is in retracted position, the shield will lie between the adjacent end of a cigarette and the ignition element, but, when the slide is withdrawn, the shield will remain in place, so that the cigarette can be ignited by the ignition element, as hereinbefore described.

The device operates with unusual smoothness and efficiency. While the slide plate 11 is in effect clamped between the false bottom 5 and the base of the rabbet 9, there is sufficient clearance to permit free sliding movement of the slide and yet the slide is held so closely to the false bottom that the resilient tongue 17 will not tend to depress the forward end of the slide, but will merely hold the same against inadvertent movement into open position. Nevertheless, when the finger piece 25 is grasped and pulled, the resilient tongue 17 will yield without undue resistance and permit the slide to be withdrawn to dispense a

cigarette. The slide is further supported against the downward pressure of the tongue 17 by the flanges 12 and 13 which ride upon the tracks 16, so as to give the slide proper bearing and appropriately guide the movements of the latter. To further preclude any tendency of the slide to twist or turn about the axis of the boss 8, the post 48 may be made long enough to project to the upper surface of the slide through the guide slot 48 10 therein, so that by this arrangement, the outer faces of the flanges 12 and 13 need not bear against the opposite end walls of the receptacle in a manner to produce undesirable friction. Thus, in quantity production, the parts may be 15 made with considerable tolerance and still will operate with thorough satisfaction. The post 48 is preferably of a length to bear against the under side of the slide and form an additional support therewith, although this is not essential.

20 The ignition element which I have described is not only simple in construction and thoroughly efficient in its operation, but is readily removable for it is simply clipped in position and the yoke can be easily sprung free from the flange 12 to 25 permit a new unit to be substituted. It will be noted from Figure 4 that the depression 33 is provided therein with a central recess 49, so that when the unit is sprung into place, the head of the rivet 31 rests in this recess, while the resiliency 30 of the yoke 30 precludes the parts from inadvertent disengagement.

While the ignition element described is simple and efficient, it is noted that the electrical contacts for feeding current to this element are 35 relatively close to the source of heat and I preferably use the alternate construction shown in Figures 13 and 14. In this construction, the flange 12 of the slide 11 is provided with a forward extension having the offset 33, but perforated, as shown at 66 in Figure 13. The contact 34 is cut 40 off slightly beyond the forward edge of the slide 11, as shown in Figure 13, and it is enclosed within an insulating sleeve 36 and projects beyond the rear end of the sleeve to form the contact 37 adapted to cooperate with the contact 38, as 45 hereinbefore described. The sleeve 36 and contact 34 are held firmly in position by two tongues 35 tightly clamped over these parts as shown and positioned in spaced relation to the forward end of the insulating sleeve. The sleeve 36 is wider 50 than the contact 34 and is crimped over the inner edge of such contact so as to preclude electrical engagement between the contact 34 and the tongues 35 and 67. Near the forward end of said sleeve, however, it is embraced by an additional tongue 67 which, relatively loosely embraces the sleeve and is of resilient character, so as to form between the wall 68 of the sleeve and the contact 34 a re-entrant mouth or female connection adapted to receive the current carrying 60 connector of the lighting element, as a slip connection. The lighting element is shown as made from sheet metal stamping comprising a circular disk 69, the center of which is pressed up to provide at the rear thereof a recess 70, and from one side of the disk extends a tail 71 provided with lateral flanges 72, the free end of one of which is cut off at an angle, as shown at 73. Against the upstanding face of the disk 69 is placed a circular disk of insulation and refractory material 74 centrally perforated for the passage of an attaching bolt 75. A strip of resistance wire 76 is secured at one end to the head of the bolt and the wire is coiled about the bolt in a spiral and thereafter passed rearwardly to lie between the flanges 72 which are thereafter pressed

firmly together to grip the wire between them and form a good electrical connection. The terminal of this wire is preferably spot welded to one of the flanges, as shown at 77, so that the tail 71 with its flanges 72 and the interposed resistance wire constitute collectively a relatively thin current carrying connector adapted to be slipped into the space between the parts 68 and 34 to make good electrical connection with the latter at a point removed from the actual 10 source of heat. This is a slip connection which may be readily accomplished.

The bolt 75 passes through an enlarged hole 78 in the disk 69 and through a perforated insulating disk 79 seated in the recess 70 to centralize the bolt and preclude its contact with the edges of the holes 78. Beyond the insulating disk 79, a threaded metal disk 80 is screwed on to the bolt and serves to hold the various parts of the element in assembled relation. The projecting portion of the bolt is adapted to be passed through the perforation 66 in the extension of the flange 12 and locked in place by a nut 81, as shown in Figure 14. To attach the element, the current carrying connector is first thrust into the female socket described to connect one terminal of the resistance coil to the current supply and the bolt is thereafter passed through the perforation 66 and the nut 81 screwed on. To remove the element for repair or replacement, the operations described are reversed.

The advantage of the alternate structure just described is that it removes the electrical contacts from the region of the heat which is generally desirable. It will of course be understood in this connection that the current is fed through the contact 34 to one of the flanges 72 and thence to the resistance wire, and after passing through the wire, is carried off through the bolt 75 to ground at the extension of the flange 12.

It will be apparent that for either of the lighting element constructions or units, which I have described, the electrical connections of the units are made without use of wiring connections which would be apt to crystallize and break if subjected to frequent bending which would be necessary due to the movement of the slide on which the element is mounted. On the contrary, the element is supported firmly in position on the slide, one terminal of the unit being grounded with respect thereto, and the other end of the unit having a definite physical contact with the spring connection which, in turn, has a wiping engagement with the fixed contact 38 in the base of the receptacle. The contact 37 does not require any great amount of flexion and will last indefinitely, while its wiping engagement with the contact 38 will serve to keep these contacts clean, so that the path of the electric current will be free from a poor contact due to corrosion, etc. The control of the current is, moreover, thoroughly satisfactory, for it is directly controlled by the movement of the slide to energize the ignition unit when the slide is pulled out and to de-energize said unit when the slide is retracted.

The lever 30 is of marked importance in a structure of this kind for it provides a highly efficient means for its intended purposes in lieu of the gears, springs and other complicated adjuncts heretofore employed to press a cigarette in the direction of an ignition element. The means which I have disclosed is practically indestructible, is subjected to minimum wear and fatigue and comprises a single moving part cam.

controlled by the stationary abutments 45 and 46.

I have hereinbefore referred to the particular skew formation of the flange 6' of the false bottom. The operation of these parts will now be clearly apparent for unless this flange were set on askew or other means provided for the same purpose, cigarettes falling into the retainers would be very apt to fall on top of the lever 39 10 and out of proper cooperative relation with this lever when the same was operated to move the cigarette into cooperative relation with the lighting element. When this flange is formed as stated, however, the cigarettes will be individually guided into proper cooperation with the lever.

I call attention to the dual function of the member 24 which serves not only as a door or closure to close the front opening 2 when the slide 20 is retracted, but also provides an efficient means for operating the slide. The door extends for the full width of the front opening and for the full height thereof and forms an efficient closure therefor imparting to the front of the device a 25 smooth and finished appearance.

The device of this invention may be supported rigidly in position in any appropriate way depending upon the particular environment in which it is employed. In Figure 1 of the drawings, I have shown one form of clamp for supporting the device on a steering post of an automobile. This clamp 50 is composed of two parts 51 and 52 adapted to collectively embrace the steering post and bracket 54. The other end of 35 the bracket is perforated to receive the bolt 7 which holds the false bottom in place and spaced on either side of the bolt 7 are tapped holes 55 formed in the base of the receptacle which may be thickened, as shown at 56, to provide proper 40 strength. The bracket may be swung from the right hand position shown in full lines in Figure 1 to the left hand position shown in dotted lines in this figure or vice versa, and secured in place by a screw 57 entering into one of the tapped 45 holes 55 to permit the mounting of the device at either the right or left hand side of the steering post where it may be firmly secured in place by the clamping parts 51 and 52. The part 51 is in the form of a U-shaped yoke provided at its 50 base with a rigid tapped block 58 through which a set screw 59 is threaded. The free end of the section 51 is returned upon itself to form a hook 60 adapted to be engaged with a simple hook 61 at the free end of the section 52 which in effect 55 constitutes a strap. The other end of the strap extends through one of the slots 62 in a corresponding end of the yoke and is thus anchored therein. The clamp 50 is tightened about the steering post by merely tightening the set screw 60 59 to cause it to press against the post and draw the strap 52 firmly about the latter. The strap, as well as a considerable portion of the yoke, is more or less yieldable to provide a spring clip, while that portion of the yoke between the block 58 and the rivet 53 is of channel cross section, so as to impart greater strength and rigidity to the support thereby provided. The rivet 65 53 is made relatively tight, so that it will properly support the bracket 54 on the clamp, but still allow of pivotal adjustment, so that the device may be adjusted to the desired inclination and permit of its association with steering posts of different inclination, and yet mount the receptacle in substantially horizontal position with its

false bottom occupying the desired slope to feed the cigarettes by gravity.

Another form of clamp which I find to be highly desirable and which in fact I prefer is that shown in Figures 15-17 of the accompanying drawings. This clamp embodies two relatively movable yokes 82 and 83 preferably formed as die castings and they are made substantially complementary in shape, so as to collectively fit about the steering post of an automobile. The yoke 82 is provided with integrally formed posts 84 operating within complementarily shaped pockets 85 in the yoke 83, so as to provide a self alining arrangement and clamping screws 86 extend through the yoke 83 and into tapped holes 87 in the yoke 82. By adjusting these screws, the two yokes may be caused to tightly and collectively grip the steering post. Spurs 88 may be formed on the interior of the yokes to cut through the enamel on the post in order to 20 obtain a good electrical ground. The clamp is secured to the receptacle 1 by means of a bolt 89 which passes through a bracket 90 similar to the bracket 54 and similarly secured to the receptacle. This bracket is provided with a keyhole slot 91, 25 shown best in Figure 16, and a nut 92 of the bolt 89 with associated washer 93 is adapted to be passed through the lower enlarged portion of this slot and then moved upwardly into the constricted part thereof. About the edges of this 30 constricted part a series of radial grooves 94 are formed in the face of the bracket and these cooperate with the lock washer 93 when the nut 92 is tightened in such manner that the parts 35 collectively function as an indexing device and a lock washer combination. The lock washer employed is of the well known kind embodying a flat plate, the peripheral edge of which is provided with teeth twisted at an angle to dig into adjacent parts when placed under compression. 40

Experience has shown that in the higher priced cars in particular, the enamel on the steering post is so heavy that it is rather difficult to break through the same in order to obtain a good electrical ground and consequently I preferably provide on the head of the bolt 89 an additional sharpened spur 96, which, when the screws 86 are tightened, is caused to cut through the enamel to a proper ground. This spur, together with the additional spurs 88, thus provide not only for the proper electrical ground, but also insure efficient gripping action of the clamp, so as it is not dependent entirely upon friction. The bolt, nut and washer combination, however, provides for a proper indexing, so that the receptacle may be 50 set at the desired angle and locked in place against inadvertent shifting with respect to the clamp. 55

I may, if desired, also associate with the device an ash tray of the character shown in Figure 12. 60 The ash tray is designated 63 and is provided at its side with a keeper 64 adapted to cooperate with the bracket 65, which may be mounted by a screw similar to the screw 57 screwed into the tapped hole in the bottom of the casing which 65 is not being used to hold the bracket 54 in place. If the clamp is swung from one side to the other, the bracket 65 for the ash tray may be moved to the other side of the device. The keeper 64 permits the ash tray to be readily removed from 70 its bracket to be emptied.

Marked advantages of the structure which I have described are its economy of manufacture, the simplicity of its parts, ease of fabrication and assembly thereof and its unfailing operation. 75

The foregoing detailed description sets forth the invention in its preferred practical form, but the invention is to be understood as fully commensurate with the appended claims.

Having thus fully described the invention, what I claim as new and desire to secure by Letters Patent is:

1. An assembly of the character described comprising a receptacle provided with a horizontal discharge opening, a false bottom within the receptacle inclined in the direction of said discharge opening and terminating in spaced relation to said opening to provide a discharge space therebetween, a slide mounted beneath the false bottom and adapted, when in retracted position, to uncover the discharge space and permit cigarettes supported on the false bottom to individually gravitate through said space, a cigarette rest carried by the forward portion of said slide to receive a cigarette as it falls through said space, said slide being slidable to project the cigarette rest through the front opening to place such cigarette in accessible position exteriorly of the receptacle, an ignition element carried by the slide at one end of the cigarette rest and movable with said slide into and out of the receptacle, and an electric circuit including said ignition element and a pair of contacts, one of which contacts is mounted on the slide and the other of which is fixed with respect to the receptacle, said contacts being so relatively positioned that, when the slide is retracted, the contacts are free from electrical engagement with one another and when the slide is withdrawn, the contacts are in electrical engagement with one another for the purpose of igniting a cigarette supported by the cigarette rest, a cigarette impelling lever movable with the slide with one end of the lever projecting to overlie the end of a cigarette remote from the ignition element and while such cigarette is supported by the rest, and the other end of said lever being offset, and stationary camming means within the receptacle cooperating with the offset end of said lever to pivotally move the lever when the slide is withdrawn for engaging said cigarette and impelling it in the direction of the ignition element.

2. An assembly of the character described comprising a receptacle provided with a horizontal discharge opening, a false bottom within the receptacle inclined in the direction of said discharge opening and terminating in spaced relation to said opening to provide a discharge space therebetween, a slide mounted beneath the false bottom and adapted, when in retracted position, to uncover the discharge space and permit cigarettes supported on the false bottom to individually gravitate through said space, a cigarette rest carried by the forward portion of said slide to receive a cigarette as it falls through said space, said slide being slidable to project the cigarette rest through the front opening to place such cigarette in accessible position exteriorly of the receptacle, an ignition element carried by the slide at one end of the cigarette rest and movable with said slide into and out of the receptacle, and an electric circuit including said ignition element and a pair of contacts, one of which contacts is mounted on the slide and the other of which is fixed with respect to the receptacle, said contacts being so relatively positioned that, when the slide is retracted, the contacts are free from electrical engagement with one another and when the slide is withdrawn, the contacts are in electrical engagement with one another for the

purpose of igniting a cigarette supported by the cigarette rest, a cigarette impelling lever movable with the slide with one end of the lever projecting to overlie the end of a cigarette remote from the ignition element and while such cigarette is supported by the rest, and the other end of said lever being offset, and stationary camming means within the receptacle cooperating with the offset end of said lever to pivotally move the lever when the slide is withdrawn for engaging said cigarette and impelling it in the direction of the ignition element, and a closure pivotally mounted on the slide and adapted to close the discharge opening of the receptacle with the ignition element, cigarette rest and impelling lever in concealed positions when the slide is in retracted position.

3. An assembly of the character described comprising a receptacle provided with a horizontal discharge opening, a false bottom within the receptacle inclined in the direction of said discharge opening and terminating in spaced relation to said opening to provide a discharge space therebetween, a slide mounted beneath the false bottom and adapted, when in retracted position, to uncover the discharge space and permit cigarettes supported on the false bottom to individually gravitate through said space, a cigarette rest carried by the forward portion of said slide to receive a cigarette as it falls through said space, said slide being slidable to project the cigarette rest through the front opening to place such cigarette in accessible position exteriorly of the receptacle, an ignition element carried by the slide at one end of the cigarette rest and movable with said slide into and out of the receptacle, and an electric circuit including said ignition element and a pair of contacts, one of which contacts is mounted on the slide and the other of which is fixed with respect to the receptacle, said contacts being so relatively positioned that, when the slide is retracted, the contacts are free from electrical engagement with one another and when the slide is withdrawn, the contacts are in electrical engagement with one another for the purpose of igniting a cigarette supported by the cigarette rest, a cigarette impelling lever movable with the slide with one end of the lever projecting to overlie the end of a cigarette remote from the ignition element and while such cigarette is supported by the rest, and the other end of said lever being offset, and stationary camming means within the receptacle cooperating with the offset end of said lever to pivotally move the lever when the slide is withdrawn for engaging said cigarette and impelling it in the direction of the ignition element, and a closure pivotally mounted on the slide and adapted to close the discharge opening of the receptacle with the ignition element, cigarette rest and impelling lever in concealed positions when the slide is in retracted position, the lower edge of the discharge opening of the receptacle being so located with respect to the closure as to exert a camming action upon the closure when the slide is moved into retracted position for the purpose of moving the closure into its closed position.

4. An assembly of the character described comprising a receptacle provided with a horizontal discharge opening, a false bottom within the receptacle inclined in the direction of said discharge opening and terminating in spaced relation to said opening to provide a discharge space therebetween, a slide mounted beneath the false

bottom and adapted, when in retracted position, to uncover the discharge space and permit cigarettes supported on the false bottom to individually gravitate through said space, a cigarette rest 5 carried by the forward portion of said slide to receive a cigarette as it falls through said space, said slide being slideable to project the cigarette rest through the front opening to place such cigarette in accessible position exteriorly of the 10 receptacle, said false bottom being provided at its front juxtaposed with said discharge space with a resilient lip adapted to engage with the corresponding edge of the forward portion of the slide when the latter is retracted to preclude inadvertent movement of the slide in a cigarette 15 dispensing direction.

5. An assembly of the character described comprising a receptacle provided with a horizontal discharge opening, a slide mounted within said 20 receptacle in inclined relation to the discharge opening and provided at one edge with a cigarette rest adapted to receive a cigarette and move the same into exposed position exteriorly of the receptacle when the slide is slid into dispensing position, an ignition element movable with said 25 slide and juxtaposed with one end of a cigarette supported on said rest, a closure pivotally mounted on the slide and adapted to close said opening when the slide is in retracted position and to open 30 said opening when the slide is in cigarette dispensing position, and a shield carried by said closure and adapted, through pivotal movement of the latter with respect to the slide, to be moved into and out of intervening relation between the 35 cigarette and ignition element to protect the cigarette from the ignition element when the slide is retracted and to permit of ignition of the cigarette by said element when the slide is in dispensing position.

40 6. An assembly of the character described comprising a receptacle provided with a horizontal discharge opening, a slide mounted within said receptacle in inclined relation to the discharge opening and provided at one edge with a cigarette rest 45 adapted to receive a cigarette and move the same into exposed position exteriorly of the receptacle when the slide is slid into dispensing position, an ignition element movable with said slide and juxtaposed with one end of a cigarette supported on said rest, a closure pivotally mounted on the slide and adapted to close said opening when the slide is in retracted position and to open said opening when the slide is in cigarette dispensing position, and a shield carried by said closure and adapted, through pivotal 50 movement of the latter with respect to the slide, to be moved into and out of intervening relation between the cigarette and ignition element to protect the cigarette from the ignition element when the slide is retracted and to permit of ignition of the cigarette by said element when the slide is in dispensing position, and a finger piece 55 on said closure to permit of operation of the slide through manipulation of the finger piece.

65 7. An assembly of the character described comprising a receptacle provided with a horizontal discharge opening, a slide mounted within said receptacle in inclined relation to the discharge opening and provided at one edge with a cigarette rest 70 adapted to receive a cigarette and move the same into exposed position exteriorly of the receptacle when the slide is slid into dispensing position, an ignition element movable with said slide and juxtaposed with one end of a cigarette supported on said rest, and a shield mounted to

be interposed between the cigarette and the ignition element when the slide is in retracted position and to be withdrawn from between the cigarette and the ignition element when the slide is in dispensing position.

8. An assembly of the character described comprising a receptacle provided with a horizontal discharge opening, a false bottom inclined in the direction of said opening, a slide mounted within said receptacle below the false bottom and in inclined parallel relation thereto to the discharge opening and provided at one edge with a cigarette rest adapted to receive a cigarette and move the same into exposed position exteriorly of the receptacle when the slide is slid into dispensing position, an ignition element movable with said slide and juxtaposed with one end of a cigarette supported on said rest, an electric circuit including said ignition element and also including two relatively movable contacts, one of which is mounted in stationary position within the receptacle and the other of which is mounted on the slide in such position that when the slide is retracted said contacts will be free from electrical connection and when the slide is in dispensing position the contacts will be in electrical engagement to insure energizing of the element when the slide is in dispensing position and de-energizing of the element when the slide is in retracted position.

9. An assembly of the character described comprising a receptacle having a discharge opening, a false bottom positioned within the receptacle and inclined toward said discharge opening and terminating short of said opening, a slide beneath the false bottom and movable from retracted position to dispensing position, and vice versa, said false bottom being provided therein with slots laterally spaced apart and extending in a direction away from said opening to provide between them an integral resilient tongue adapted to engage with the slide to preclude inadvertent sliding movement thereof, and projections formed on the slide and projecting through said slots into engagement with cigarettes supported on the false bottom for the purpose of agitating said cigarettes as the slide is operated.

10. An assembly of the character described comprising a receptacle having a horizontal discharge opening, a false bottom inclined in the direction of said opening and extending rearward from the upper edge of the latter and in spaced relation thereto, a slide operating as a valve across said space and provided at its forward edge with a rest to receive a cigarette from the false bottom through said space when the slide is in retracted position and to move said cigarette into exposed position when the slide is in dispensing position, an ignition element movable with the slide and mounted at one end of the rest, and a cigarette impelling lever also movable with the slide and with the cigarette therein and mounted at the other end of the rest to impel a cigarette on the rest into engagement with the ignition element when the slide is moved into dispensing position.

11. An assembly of the character described comprising a receptacle provided with a horizontal discharge opening, a slide mounted within said receptacle in inclined relation to the discharge opening and provided at one edge with a cigarette rest adapted to receive a cigarette and move the same into exposed position exteriorly of the receptacle when the slide is slid into dispensing position, an ignition element movable

with said slide and juxtaposed with one end of a cigarette supported on said rest, and a shield mounted within the casing in a stationary position between the ignition element and a cigarette supported in the rest when the slide is in retracted position to protect such cigarette from contact with the element.

12. An assembly of the character described comprising a receptacle provided with a horizontal 10 discharge opening, a fixed false bottom within the receptacle inclined in the direction of said discharge opening and terminating in spaced relation to said opening to provide a discharge space therebetween, a slide mounted beneath the 15 false bottom in parallel relation thereto and adapted, when in retracted position, to uncover the discharge space and permit cigarettes supported on the false bottom to individually gravitate through said space, a cigarette rest carried 20 by the forward portion of said slide to receive a cigarette as it falls through said space, said slide being slidable to project the cigarette rest through the front opening to place such cigarette in accessible position exteriorly of the receptacle, 25 and an ignition element carried by the slide at one end of the cigarette rest and movable with said slide into and out of the receptacle.

13. An assembly of the character described comprising a receptacle provided with a horizontal 30 discharge opening, a false bottom within the receptacle inclined in the direction of said discharge opening and terminating in spaced relation to said opening to provide a discharge space therebetween, a slide mounted beneath the false 35 bottom and adapted, when in retracted position, to uncover the discharge space and permit cigarettes supported on the false bottom to individually gravitate through said space, a cigarette rest carried by the forward portion of said slide 40 to receive a cigarette as it falls through said space, said slide being slidable to project the cigarette rest through the front opening to place such cigarette in accessible position exteriorly of the receptacle, and a closure pivotally mounted on the 45 slide and adapted to close the discharge opening of the receptacle when the slide is in retracted position.

14. An assembly of the character described comprising a receptacle provided with a horizontal 50 discharge opening, a false bottom within the receptacle inclined in the direction of said discharge opening and terminating in spaced relation to said opening to provide a discharge space therebetween, a slide mounted beneath the false 55 bottom and adapted, when in retracted position, to uncover the discharge space and permit cigarettes supported on the false bottom to individually gravitate through said space, a cigarette rest carried by the forward portion of said slide to 60 receive a cigarette as it falls through said space, said slide being slidable to project the cigarette rest through the front opening to place such cigarette in accessible position exteriorly of the receptacle, and a closure pivotally mounted on the 65 slide, the lower edge of the discharge opening of the receptacle being so located with respect to the closure as to exert a camming action upon the closure when the slide is moved into retracted

position for the purpose of moving the closure into its closed position.

15. A cigarette dispenser and lighter comprising a container for cigarettes, a reciprocable receiver adapted to receive the cigarettes individually from the container, an ignition element at one end of said receiver, a pusher element shiftable longitudinally of the receiver and supported thereon, and means for actuating the pusher to move the cigarette into cooperative relation with the ignition element and for simultaneously energizing the ignition element. 5

16. A cigarette dispenser and lighter comprising a container for cigarettes, a reciprocable receiver adapted to receive the cigarettes individually from the container, an ignition element supported at one end of said receiver, a pusher supported on the other end of said receiver, means operable upon movement of the receiver to actuate the pusher to move a cigarette in the receiver into cooperative relation with the ignition element, and means also operable upon movement of the receiver to energize the ignition element. 10

17. A cigarette dispenser and lighter comprising a container for cigarettes, a reciprocable receiver for segregating for delivery a single cigarette from the container, normally inactive ignition means at one end of the receiver, a pusher carried by the receiver and operable at the other end thereof to longitudinally move a cigarette in the receiver into cooperative relation with the ignition means. 15

18. A cigarette dispenser comprising a receptacle provided with a discharge outlet and adapted to hold cigarettes, a dispenser movable through the outlet to project exteriorly of said outlet and support a cigarette in dispensed condition, a closure for said outlet pivoted to and carried by the dispenser and constituting an operating member 20 to impart movement to the dispenser. 35

19. A cigarette dispenser comprising a container for cigarettes provided with a discharge outlet, a slide mounted for sliding movement and adapted to receive cigarettes from the container and deliver them through the discharge outlet, and a closure for said outlet, said closure being pivotally supported on and operatively connected to the slide and forming a handle whereby the 45 slide may be operated. 50

20. A cigarette dispenser and lighter comprising a cigarette container having at its bottom a downwardly and forwardly inclined receiver provided in its front end with a dispensing trough normally positioned to receive cigarettes individually from the container, said receiver being bodily movable to shift the trough downwardly and outwardly of the container to dispense such cigarettes individually and simultaneously act to retain the other cigarettes in the container, a normally inactive igniter at one end of the trough 55 spaced from the adjacent end of a cigarette resting in the trough, and a pusher carried by said receiver and adapted to engage the other end of such cigarette and shift it longitudinally in the 60 trough into igniting relation with the igniter. 65

RICHARD MAYER.
